(57) **CLAIM**

The ornamental design for a stand for dental instrument, as
shown and described.

DESCRIPTION

FIG. 1 is a perspective view of a stand for dental instrument
showing the claimed design;

FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof; and,

FIG. 8 is a perspective reference view of the stand for dental
instrument of the present invention showing the claimed
design in an environment in which it may be used.

The broken lines in the figures show portions of the stand for
dental instrument and environment that form no part of the
claimed design.
